COOLANT SUPPLY AND EXHAUST DISCHARGE
MEANS FOR INBOARD-OUTBOARD DRIVES
Elmer Carl Kickhaefer, Winter Haven, Fla., assignor to
Kickhaefer Corporation, Fond du Lac, Wis., a corpora-
tion of Delaware

Filed Jan. 7, 1963, Ser. No. 249,726
12 Claims. (Cl. 115—34)

This invention relates to inboard-outboard drives for watercraft and wherein the steering and tilt axes of the stern drive unit are disposed forwardly of the vertical drive shaft of the unit and more particularly to the cooling and exhaust systems for such drives.

In inboard-outboard drives wherein the steering and tilt axes of the stern drive unit are disposed forwardly of the vertical drive shaft of the unit, the generally horizontal drive connection between the inboard engine and the stern drive unit must be adapted to accommodate steering and tilt movements of the unit. Where the stern drive unit includes cooling water supply means for the engine and engine exhaust discharge means, the respective means, like the horizontal drive connection, must also accommodate movements of the stern drive unit. It is generally an object of this invention to provide coolant supply means and exhaust discharge means for the inboard engine in the outboard or stern drive unit fully capable of accommodating tilt and steering movements of the drive unit on axes disposed forwardly of the vertical drive shaft of the drive unit.

According to the invention, a stern drive unit suspended from the transom of a watercraft and having steering and tilt axes forwardly of the vertical drive shaft of the unit includes an engine exhaust discharge passage for conducting exhaust gases to a discharge opening beneath the water surface and water coolant supply means for the engine. The stern drive unit is provided with an exhaust inlet and coolant supply outlet which are movable with the unit in accordance with steering and tilt movements of the unit. Conduit means extending through the transom are provided which connect the stern drive exhaust inlet to the corresponding exhaust outlet on the engine and the stern drive coolant outlet to the corresponding coolant inlet on the engine. The coolant and exhaust conduit means connecting the stern drive unit and the engine are flexible in the region of the steering and tilt axes of the stern drive unit so that the respective conduit means are fully capable of accommodating the steering and tilt movements of the unit without disruption of the coolant and exhaust systems.

The drawings furnished herewith illustrate the best mode for carrying out the invention as presently contemplated and set forth hereinafter.

In the drawings:

FIGURE 1 is a perspective view of a stern drive unit of an inboard-outboard drive mounted on the partially shown transom of a watercraft;

FIG. 2 is an enlarged sectional view in elevation of an inboard-outboard drive mounted on the transom of a watercraft and showing portions of the coolant supply and exhaust systems of this invention;

FIG. 3 is an elevational view of an inboard-outboard drive and generally shows the inboard portion of the coolant supply and exhaust systems for the inboard engine;

FIG. 4 is a view taken generally on line 4—4 of FIG. 2 and shows the exhaust conduit and coolant supply conduit as they enter the watercraft through the inner transom plate;

FIG. 5 is a view taken generally on line 5—5 of FIG. 2;

FIG. 6 is a view taken generally on line 6—6 of FIG. 2; and

2

FIG. 7 is a detail view showing the coolant supply line as it passes through the transom plate assembly.

Referring to the drawings, the inboard-outboard drive includes a stern drive unit 1 mounted on the transom 2 of a partially shown boat or other watercraft 3. The stern drive unit includes a propeller 4 which is carried rearwardly on the generally horizontal propeller shaft 5 driven by the generally vertical drive shaft 6 through drive gear 7 on shaft 6 and spaced forward and reverse driven gears 8 and freely rotatable on the propeller shaft. A clutch element 10 is rotatably carried by the propeller shaft 5 intermediate the driven gears 8 and 9 and is movable axially to selectively engage the driven gears and drive propeller 4 in opposed directions corresponding to forward and reverse propulsion in accordance with clutch engagement.

The vertical drive shaft 6 is driven by the engine 11 mounted inboard of the watercraft 3 through the horizontal drive shaft 12 extending through the transom and the meshing bevel gears 13 and 14 carried on shafts 6 and 12 respectively within gear chamber 15. The horizontal drive shaft 12 includes a double universal joint 16 having its center substantially at the intersection of the generally vertical steering axis and generally horizontal tilt axis of the stern drive unit 1 as will be more fully described hereinafter.

The stern drive unit 1 is supported from the transom 2 by opposed inner and outer transom plates 17 and 18, respectively disposed on opposite sides of the transom and overlying the transom opening 19 and secured to each other and to the transom by means of suitable bolts 20.

The inner transom plate 17 includes a pair of transversely spaced forwardly extending arms 21 and 22 providing mounting support for the rear end of engine 11 and for the proper longitudinal alignment of the engine relative to the transom plate assembly. The outer transom plate 18 includes a generally tubular pilot projection 23 which is stepped outwardly adjacent the rear end thereof to provide a retaining well 24 for the ball bearing 25 rotatably supporting the horizontal drive shaft 12 generally centrally within the tubular projection. The tubular projection 23 is telescopingly received by the opening 26 in the inner transom plate 17 to provide for proper alignment of drive shaft 12 relative to the coupling element 27 carried by the engine flywheel 28.

Outer transom plate 18 constitutes a gimbal ring housing for the gimbal ring member 29 which extends around drive shaft 12 at joint 16 and is disposed intermediate the transom plate 18 and the stern drive unit 1. The gimbal ring member 29 is adapted to receive therewithin the forward portion of bell housing 30 for pivotal support of the drive unit on a pair of transversely spaced pin members 31 carried by the gimbal ring member and disposed on the generally transverse horizontal tilt axis. The tilt axis is generally disposed at the line of intersection of the transverse vertical and horizontal central planes through the double universal joint 16 in drive shaft 12 so that the drive can bend readily at the joint to accommodate tilt movements of the unit in a generally vertical plane as when striking a submerged or floating object.

The gimbal ring member 29 is in turn pivotally supported from the outer transom plate 18 by vertically spaced and axially aligned shaft elements 32 and 33 disposed on a generally vertical swivel axis for rotation of the gimbal ring together with the stern drive unit in a generally horizontal plane for steering control of the unit. The swivel axis is disposed ahead of the vertical drive shaft 6 and passes generally through the center of the double universal joint 16 so that the horizontal drive

shaft 12 bends correspondingly at the joint to accommodate steering movements of the unit. Steering control of the unit is provided by remote control means which pivots the steering arm 34 secured on swivel shaft element 32.

According to this invention, the stern drive unit having steering and tilt axes ahead of the vertical drive shaft of the unit is adapted to receive the exhaust products from the inboard engine 11 for discharge beneath the water surface and the engine cooling water is picked up by the drive unit and conducted to the engine.

The exhaust products resulting from engine operation are discharged from engine 11 through the exhaust pipe 35 which extends rearwardly and downwardly from the engine. Exhaust pipe 35 is disposed to the side of the horizontal drive shaft 12 and the flexible conduit 36 is connected thereto and extends downwardly and around the drive shaft and engine coupling element 27. Conduit 36 passes through opening 37 in the lower portion of inner transom plate 17 and into transom opening 19 for connection to the forward projection of tubular connector 38 which is aligned with opening 37 and formed integrally with the outer transom plate 18 about an axis in the vertical plane containing the axis of drive shaft 12.

The dirigible and tiltable stern drive unit 1 is provided with an inlet 39 for engine exhaust products in the lower portion of bell housing 30 which is generally in alignment with and of the same size as the rearward projection of transom plate connector 38. An expandable bellows conduit 40 extends through the gimbal ring member 29 and connects the fixed transom plate connector 38 and movable stern drive inlet 39 providing passage for the exhaust products from engine 11 to the interior of the stern drive unit without interference from or to steering and tilt movements of the drive unit.

In the interior of the stern drive unit 1, the exhaust products move downwardly and are directed into the propeller hub passages 41 for discharge under water from the discharge opening 42 rearwardly of the propeller 4.

The water for engine cooling is picked up through a series of vertically spaced openings 43 provided on each side of the stern drive unit 1 beneath the anti-cavitation plate 44. The openings 43 communicate with a vertically extending internal cored passage 45 which conducts the water to the impeller pump 46 driven by vertical drive shaft 6. Pump 46 forces the coolant through the upwardly extending tubular member 47 into chamber 48 which is disposed rearwardly of and adjacent to the gear chamber 15 to provide for cooling of the latter chamber.

From cooling chamber 48, the cooling water flows through the transverse passage 49 into the longitudinal passage 50 extending along the side of the gear chamber 15. Passage 50 terminates with a forwardly extending tubular projection 51 opening within the stern drive bell housing 30 generally between horizontal drive shaft 12 and the exhaust inlet 39 and to the right of the vertical plane through the axis of shaft 12 as viewed in FIG. 5.

A flexible conduit 52 extends through gimbal ring member 29 and spans the distance between the fitting 53 threaded into projection 51 movable with the dirigible and tiltable stern drive unit 1 and the tubular fitting 54 secured within the generally fixed outer transom plate 18 above horizontal drive shaft 12 and on the opposite side of the vertical plane through the axis of shaft 12 from projection 51. Conduit 52 is clamped onto fitting 53 and extends forwardly and around the bellows connector 55 extending between the stern drive bell housing 30 and the outer transom plate 18 and enclosing the horizontal drive shaft 12 at the double universal joint 16. The end portion of conduit 52 adjacent to transom plate 18 generally parallels the plate and is clamped to angular fitting portion 56 which opens generally normal to a radial

line through the axis of the horizontal drive shaft so that conduit 52 spans the distance from the movable stern drive unit relatively smoothly and is substantially free from kinks. Since the fittings 53 and 54 are disposed generally equidistantly and oppositely with respect to the vertical and horizontal planes through the axis of drive shaft 12, conduit 52 will not be unduly stressed during steering and tilt movements of the propulsion unit.

The fitting 54 carries the coolant through the outer transom plate 18 and is mounted within the outer transom plate projection 57 which extends inboard through the opening 58 in the inner transom plate 17. The fitting 54 is disposed in a frusto-conical rubber bushing 59 which is adapted to be wedged into the tapered opening 60 through projection 57 to securely hold the fitting and prevent water from leaking through opening 60 into the interior of the watercraft. An elliptical plate 61 having an opening 62 to pass over fitting 54 is adapted for securement to the forward face of projection 57 to compress the bushing 59 into intimate contact with the fitting and the wall forming opening 60 in the projection.

Forwardly of the transom plate assembly, fitting 54 includes an angular portion 63 which extends upwardly and to the right as viewed in FIG. 4 to eliminate undue kinking in the flexible conduit 64 clamped to fitting portion 63. Conduit 64 extends forwardly and around the side of engine 11 for connection to the engine pump 65 which circulates the coolant through appropriate engine passages, not shown. After the coolant has served its purpose within engine 11, the heated water is discharged into the engine exhaust pipe 35 through conduit 66 connecting the pipe with the engine outlet 67. The discharged coolant thus serves to cool the engine exhaust products flowing through the exhaust pipe and passes through the exhaust system for discharge from the stern drive unit with the exhaust products.

With the structure of this invention wherein the exhaust products pass through the stern drive unit for underwater discharge a more quiet engine operation results without need for a separate muffler to take up space in the watercraft. Provision for coolant pickup in the stern drive unit eliminates the need for a separate pickup on the watercraft where such would not only be vulnerable to damage but also would impose a substantial drag upon the progress of the watercraft. With a coolant water pickup in the stern drive unit, the coolant also becomes conveniently available to cool the upper gear case in the unit.

Various modes of carrying out the invention are contemplated as being within the scope of the following claims particularly pointing out and distinctly claiming the subject matter which is regarded as the invention.

I claim:

1. In an inboard-outboard drive for watercraft, an engine disposed inboard of the watercraft, a propulsion unit disposed outboard of the watercraft and dirigibly and pendently supported therefrom for steering movement on a generally vertical axis and for tilt movement on a generally horizontal transverse axis substantially intersecting said steering axis, a substantially vertical drive shaft in said propulsion unit rearward from said steering axis, drive means interconnecting said engine and said propulsion unit drive shaft, mounting means for said propulsion unit secured to the transom of the watercraft and surrounding an opening through said transom for receiving said drive means, water pick-up means in said propulsion unit, a water pump in said propulsion unit driven by said drive shaft and connected to receive water from said pick-up means, means to conduct water from said pump through the propulsion unit and through the transom opening and said mounting means to said engine and including flexible conduit means adjacent said axes intersection to provide freedom for steering and tilt movements of said propulsion unit upon said axes.
2. In an inboard-outboard drive for watercraft, an en-

gine disposed inboard of the watercraft, a propulsion unit disposed outboard of the watercraft and dirigibly and pendently supported therefrom for steering movement on a generally vertical axis and for tilt movement on a generally horizontal transverse axis substantially intersecting said steering axes, a substantially vertical drive shaft in said propulsion unit rearwardly of said steering axis, drive means interconnecting said engine and said propulsion unit drive shaft, mounting means for said propulsion unit secured to the transom of the watercraft and surrounding an opening through said transom for receiving said drive means, and engine exhaust passage means extending from said engine through said transom opening and said mounting means into and through said propulsion unit and including a flexible and expandable conduit section adjacent to said axes intersection to provide freedom for steering and tilt movements of said propulsion unit upon said axes without interruption of said passage means.

3. In an inboard-outboard drive for watercraft having a transom, an engine disposed inboard of the watercraft, a propulsion unit disposed outboard of the watercraft and having an anti-cavitation plate and a vertical drive shaft and being dirigibly and pendently supported from the transom on generally vertical and transverse horizontal axes forwardly of said drive shaft, a horizontal drive shaft extending through the transom and drivingly connecting the vertical drive shaft and said engine and being adapted to accommodate movements of the propulsion unit on said axes, mounting means for said propulsion unit secured to said transom and surrounding an opening through the transom for said horizontal drive shaft, pickup means for engine cooling water in said propulsion unit beneath the anti-cavitation plate, outlet means on said propulsion unit above the anti-cavitation plate and communicating with said cooling water pickup means, and conduit means extending through said transom opening and said mounting means and connecting the propulsion unit outlet means to the engine for carrying the cooling water to the engine, said conduit means being adapted to flex in the region of said generally vertical and transverse horizontal axes as not to interfere with the steering and tilt movements of the propulsion unit.

4. In an inboard-outboard drive for watercraft having a transom, an engine disposed inboard of the watercraft, a propulsion unit disposed outboard of the watercraft and having an anti-cavitation plate and a vertical drive shaft and being dirigibly and pendently supported from the transom on generally vertical and transverse horizontal axes forwardly of said drive shaft, a horizontal drive shaft extending through the transom and drivingly connecting the vertical drive shaft and said engine and being adapted to accommodate movements of the propulsion unit on said axes, mounting means for said propulsion unit secured to said transom and surrounding an opening through the transom for said horizontal drive shaft, engine exhaust discharge means in said propulsion unit beneath the anti-cavitation plate, inlet means on said propulsion unit above the anti-cavitation plate and communicating with said exhaust discharge means, and conduit means extending through said transom opening and said mounting means and connecting the propulsion unit inlet means to the engine exhaust pipe and carrying the engine exhaust products to the propulsion unit for discharge under water, said conduit means being adapted to flex and expand in the region of said generally vertical and transverse horizontal axes so as not to interfere with the steering and tilt movements of the propulsion unit.

5. In an inboard-cutboard drive for watercraft having a transom, an engine disposed inboard of the watercraft, a propulsion unit disposed outboard of the watercraft and having an anti-cavitation plate and a vertical drive shaft, mounting means for said propulsion unit secured to said transom and surrounding an opening through the transom, said propulsion unit being dirigibly and pendently supported by said mounting means on generally

vertical and transverse horizontal axes forwardly of said drive shaft, a horizontal drive shaft extending through the transom opening and drivingly connecting the vertical drive shaft and said engine and being adapted to accommodate movements of the propulsion unit on said axes, pickup means for engine cooling water and engine exhaust discharge means in said propulsion unit beneath the anti-cavitation plate, cooling water outlet means on said propulsion unit above the anti-cavitation plate and communicating with said cooling water pickup means, exhaust inlet means on said propulsion unit above the anti-cavitation plate and communicating with said exhaust discharge means, conduit means extending through the transom opening and mounting means and connecting the propulsion unit outlet means to the engine for carrying cooling water to the engine, and conduit means extending through the transom opening and mounting means and connecting the propulsion unit inlet means to the engine exhaust pipe for carrying the engine exhaust products to the propulsion unit for discharge under water, said respective conduit means being adapted to flex in the region of said generally vertical and transverse horizontal axes so as not to interfere with the steering and tilt movements of the propulsion unit.

25 6. In an inboard-outboard drive for watercraft having a transom, an engine disposed inboard of the watercraft, a propulsion unit disposed outboard of the watercraft and having an anti-cavitation plate and a vertical drive shaft, support means mounted on the transom and dirigibly and pendently supporting the propulsion unit on generally vertical and transverse horizontal axes forwardly of said vertical drive shaft, a horizontal drive shaft extending through said transom and support means and drivingly connecting the vertical drive shaft and said engine and being adapted to accommodate steering and tilt movements of the propulsion unit on said axes, pickup means for engine cooling water and discharge means for engine exhaust in said propulsion unit beneath the anti-cavitation plate, cooling water outlet means on said propulsion unit above the anti-cavitation plate and communicating with said cooling water pickup means, exhaust inlet means on said propulsion unit above the anti-cavitation plate and communicating with said exhaust discharge means, said propulsion unit support means including through transom cooling water passage means and exhaust passage means respectively communicating with the engine, and flexible conduit respectively connecting the propulsion unit cooling water outlet means to the cooling water passage means and the propulsion unit exhaust inlet means to the exhaust passage means so as not to interfere with the steering and tilt movements of the propulsion unit.

30 7. The invention of claim 6 wherein the driving connection between the horizontal and vertical drive shafts consists of meshing gears disposed within a chamber in the propulsion unit and the cooling water flowing through the propulsion unit between the pickup means and outlet means is conducted through passage means in heat interchange relation with the gear chamber.

35 8. In an inboard-outboard drive for watercraft having a transom, an engine disposed inboard of the watercraft, a propulsion unit disposed outboard of the watercraft and having an anti-cavitation plate and a vertical drive shaft, support means mounted on the transom, a gimbal ring member pivotally supporting the propulsion unit on a generally transverse horizontal axis to accommodate tilt movements of the unit in a generally vertical plane and being pivotally supported by the support means on a generally vertical axis to accommodate steering movements of the member together with the propulsion unit in a generally horizontal plane, a horizontal drive shaft extending through said transom and gimbal ring member and drivingly connecting the vertical drive shaft and said engine and having universal coupling means to accommodate steering and tilt movements of the propulsion unit on said axes, pickup means for engine cooling

water and discharge means for engine exhaust provided in the propulsion unit beneath the anti-cavitation plate, cooling water outlet means on said propulsion unit above the anti-cavitation plate and communicating with said cooling water pickup means, exhaust inlet means on said propulsion unit above the anti-cavitation plate and communicating with said exhaust discharge means, said transom support means including through transom cooling water passage means and exhaust passage means respectively communicating with the engine, and flexible conduit extending through the gimbal ring member and connecting the propulsion unit cooling water outlet means to the cooling water passage means and the propulsion unit exhaust inlet means to the exhaust passage means to provide for uninterrupted flow of coolant and exhaust products respectively and without interference to the steering and tilt movements of the propulsion unit.

9. The invention of claim 8 wherein the driving connection between the horizontal and vertical drive shafts consists of meshing gears disposed within a chamber in the propulsion unit and the cooling water flowing through the propulsion unit between the pickup means and outlet means is conducted through passage means in heat interchange relation with the gear chamber.

10. The invention of claim 8 wherein the propulsion unit exhaust inlet means and the exhaust passage means in the transom support means are longitudinally aligned and disposed on an axis beneath and generally in the vertical plane of the axis of the horizontal drive shaft and the flexible conduit connecting said inlet means and passage means is a bellows connector.

11. The invention of claim 8 wherein the propulsion unit cooling water outlet means opens forwardly and is

disposed beneath the horizontal drive shaft and to one side of the vertical plane through the axis of said shaft and the cooling water passage means in the transom support means constitutes a fitting disposed above said shaft and on the opposite side of the vertical plane through the axis of said shaft from said outlet means, said fitting having an outboard end portion which opens generally normal to a radial line through the axis of the horizontal drive shaft so that the flexible conduit connecting the outlet means and fitting and extending around the horizontal drive shaft is substantially free of kinks.

12. The invention of claim 8 wherein the cooling water outlet means on the movable propulsion unit and the cooling water passage means on the generally fixed transom support means are disposed generally equidistantly and oppositely with respect to vertical and horizontal planes through the axis of the horizontal drive shaft so that the flexible conduit extending therebetween is not unduly stressed during tilt and steering movements of the unit.
